ELECTRICAL APPARATUS

Raymond P. Lansing, Montclair, N. J., assignor,
by mesne assignments, to Eclipse Aviation Corporation,
East Orange, N. J., a corporation of
New Jersey

Application June 25, 1932, Serial No. 619,329

6 Claims. (Cl. 200—87)

This invention relates to electromagnetic apparatus, and more particularly to the mechanical construction of such apparatus.

The object of the invention is to provide improvements in the mechanical construction and serviceability of electromagnetic apparatus. These improvements are of particular utility when applied to an electromagnet of the type adapted to alternately make and break one or more electrical circuits, but it will be apparent from the following specification and the appended claims that the invention is not limited to such application, as the improvements herein-after recited are also capable of embodiment in any electromagnet of the specified character whether for switch operation or for other purposes.

In the accompanying drawing, wherein the preferred embodiment of the invention is illustrated, and wherein like reference characters refer to like parts throughout the views:

Fig. 1 is a vertical longitudinal sectional view taken on the line 1—1 of Fig. 3;

Fig. 2 is a view in elevation at right angles to the viewpoint of Fig. 1; and

Fig. 3 is a top plan view of the parts shown in Figs. 1 and 2, one of which is broken away to clarify the illustration.

In the drawing the electromagnet is shown as mounted on and supported by a bracket 57 that is suitably attached to the panel 38. Surrounding the core 56 are a pair of coils 58 and 59, the former preferably being of heavy wire and the latter being formed of several turns of fine wire, the two coils being wound in opposite directions with one superimposed on the other, as indicated in Fig. 1. Extending across the upper end of core 56 is an armature 61 with which is associated novel means whereby it is suspended for limited oscillation in bearing surfaces formed in a U-shaped block 62 riveted as indicated at 63, to the vertical leg of the L-shaped plate 91, the lower leg of which is apertured to receive the reduced end 92 of the core 56. Screws 93 passing through mounting bracket 57 hold the plate 91 in position beneath the base plates 94 and 95 of the unit, while a similar screw 97, aided by a member 98, secures the core to the L-shaped member 91; the members 57 and 91 being preferably disposed with their vertical portions at right angles, as shown best in Fig. 2.

The novel means for suspending the armature 61 to permit limited movement thereof about its pivot connection in response to the resultant of the opposing electro-magnetic force exerted

thereon, includes weighted members 99 and 100—100 secured to the armature on opposite sides of line of axis of the upstanding ears or lugs 101 which receive the pin 102, by which the armature is suspended in the bearing members 62, above described. As shown, the weights 100—100 in addition to their function of acting as a counter-balance for the weight 99, also serve to hold the movable switch element 104 in spaced relation to the armature 61. As shown, the switch element 104 is composed of a series of laminations of conducting material held together by suitable means 105 and 106, the latter being shown as a rivet which also holds in place a contact button 107, adapted to engage a corresponding button 108 riveted to a conducting terminal bar 109 which serves for attachment of a lead of one of the circuits to be more fully described, and is in turn supported on a plate 112 to which the upper end of the core 56 is peened, as indicated at 113, and which forms, with said core part of the magnetic circuit; the bar 109 being insulated by members 114, attached to plate 112 by suitable means such as screws 115, shown in Fig. 3.

Supplementing the weight 99 in opposing the tendency of the armature 61 to move toward the core 56 upon energization of the electro-magnet is a tension spring 118, the upper end of which is held to a finger 119, depending from the outer portion of the armature 61, the lower end of the spring being received in a rectangular block 121 adapted to have limited movement within an opening in the upper leg of a U-shaped bracket 123, the central portion of which is secured to the member 91 by suitable means 124, which also serves to secure and hold a pawl 127 in locking relation to the serrated edge of an adjusting disc 128 which turns with a screw 129. The screw 129 has a shank which extends through the lower leg 131 of the U-shaped bracket. Formed in this shank is a threaded socket 132 engaging a correspondingly threaded end 134 of the block 121 so that upon turning of the screw 129, a raising or lowering of the block 121, and hence a variation in the tension of the spring 118 is effected; the pawl 127 acting to hold the weight in the adjusted position by virtue of its locking engagement with the disc 128.

Preferably a compression spring 139 is coiled about the shank of the screw 129 so that its upper end presses upon disc 140. The disc in turn bears against the under surface of the block 121 and thus yieldably opposes the gravitational force of the block. In addition to this yieldable

opposition, there is also provided a positive stop limiting the extent of oscillation of the armature 61 in one direction, such stop being shown in the form of a bent strip 143, the upper end of which 5 is normally in contacting relation to the under surface of the armature 61, and the lower end of which is secured to the member 91 by suitable means, herein shown in conjunction with the strip 146 secured to the plate 91 as by rivets 145; 10 the said strip 146 serving for the attachment of the ends of leads 148-148, as shown at 153-153, the other ends of which are secured to clips 141-141 of a bar 142 riveted in conjunction with the laminated contact piece 104, and weights 15 100-100, to the armature 61, as indicated at 152 in Figs. 3 and 5. One of the clips 153 may also serve for the attachment of the lead 154, to which one end of the winding 58 is secured.

In order to make it possible to readily remove 20 the armature 61 and the parts assembled therewith and without the necessity of interfering with the main unit, the pin 102 from which the armature is suspended is preferably bent at an approximate right angle, as indicated at 157 in Fig. 5, the outer end thereof being held between the concave surfaces of a pair of resilient detents 159 and 160, shown best in Fig. 4, the said detent being secured in any suitable manner, preferably being clamped between the weight 99 and armature 61, as indicated at 99' in Fig. 3.

When the electromagnetic switch shown in the drawing is applied to the control of a battery charging circuit, it is in the nature of a reverse current relay, the current or "series" coil being 35 the one indicated at 58, while the voltage or "shunt" coil is the one indicated at 59. Coil 58 normally assists coil 59 in holding contacts 107-108 more firmly closed than said contacts can be held by the shunt coil alone. If the amount 40 of current delivered to the battery or load circuit decreases, due for example to a decrease in the speed of the generator armature, there is a tendency for current to flow from the battery through the series coil 58, whereby the latter sets up a field which coacts with spring 118 to open contacts 107 and 108. After these last named contacts are opened, the current for the load circuit is provided by the battery, but the charging of the battery is automatically resumed as 45 soon as the voltage through shunt coil 59 is sufficiently high to again close contacts 107 and 108 against the tension of spring 118.

What is claimed is:

1. In apparatus of the class described, a magnet, a support therefor, an armature pivoted to 55 said support, a pair of weights mounted on said armature on opposite sides of the pivotal axis thereof and tending to maintain equilibrium therein, a removable pivot pin for journaling said armature in said support, and means associated with one of said weights for yieldably holding 60 said pin against axial displacement.

2. In apparatus of the class described, a magnet, a support therefor, an armature pivoted to said support, a pair of weights mounted on said armature on opposite sides of the pivotal axis thereof and tending to maintain equilibrium therein, a removable pivot pin for journaling 5 said armature in said support, and means associated with one of said weights for yieldably holding said pin against axial displacement, said holding means also acting to hold said pin against 10 rotary movement, except in synchronism with said armature.

3. In apparatus of the class described, a magnet, a support therefor, an armature pivoted to 15 said support, a pair of weights mounted on said armature on opposite sides of the pivotal axis thereof and tending to maintain equilibrium therein, a spring catch extending from said armature, and a pin engageable with said catch for security and ready removal, said armature 20 being suspended from said pin.

4. In apparatus of the class described, a magnet, a support therefor, an armature pivoted to 25 said support, a pair of weights mounted on said armature on opposite sides of the pivotal axis thereof and tending to maintain equilibrium therein, a coiled spring connecting with said armature to assist said weights in maintaining 30 said armature in a predetermined position, a third weight secured to the end of said spring remote from said armature, said weight acting to maintain said spring at the predetermined tension, and additional resilient means opposing the gravitational force on said third weight and thereby damping the vibrational tendencies 35 thereof.

5. In apparatus of the class described, a magnet, a support therefor, an armature pivoted to 40 said support, a coiled spring connecting with said armature to tend to maintain said armature in a predetermined position, a weight secured to the end of said spring remote from said armature, said weight acting to maintain said spring at the predetermined tension, and additional 45 resilient means opposing the gravitational force on said weight and thereby damping the vibrational tendencies thereof.

6. In apparatus of the class described, a magnet, a support therefor, an armature pivoted to 50 said support, a tensioned spring connecting with said armature to tend to maintain said armature in a predetermined position, a weight acting to maintain 55 said spring at the predetermined tension, a threaded extension on said weight, said extension being disposed concentrically of said weight, a member engageable with said threaded extension to regulate the tensioning effect of said weight upon said spring, and a second spring surrounding said threaded extension and acting as a cushion for said weight.

RAYMOND P. LANSING.
